UNITED STATES PATENT OFFICE.

LOUIS A. CASGRAIN, OF BEVERLY, MASSACHUSETTS, ASSIGNEE, BY MESME ASSIGNMENTS, TO UNITED SHOE MACHINERY CORPORATION, OF PATERSON, NEW JERSEY, A CORPORATION OF NEW JERSEY.

MACHINE FOR BREASTING THE HEELS OF BOOTS AND SHOES.

1,289,652.

Specification of Letters Patent. Patented Dec. 31, 1918.

Application filed March 22, 1915. Serial No. 16,102.

To all whom it may concern:

Be it known that I, LOUIS A. CASGRAIN, a citizen of the United States, residing at Beverly, in the county of Essex and State of Massachusetts, have invented certain Improvements in Machines for Breasting the Heels of Boots and Shoes, of which the following description, in connection with the accompanying drawings, is a specification, like reference characters on the drawings indicating like parts in the several figures.

This invention relates to machines for use in the manufacture of boots and shoes and is herein shown as embodied in a machine for breasting heels.

The general object of the invention is to produce a breasting machine which will perform its work more rapidly and accurately than has been possible with prior machines and one upon which the best class of work may be produced by an operator who is comparatively unskilled.

In the use of prior machines the chips which are severed from the heel breast in the breasting operation have been allowed when completely severed to fall at random upon the floor, and when, as is often the case, the chip is not completely severed but still clings more or less securely to the heel along the shank the operator has been obliged to seize and tear the chip from the shoe at the expense of considerable time and annoyance. It has been proposed, I am aware, to employ mechanism such as is shown in United States Letters Patent No. 958,306, granted May 17, 1910, to Thomas G. Plant. This mechanism, however, is not as effective as may be desired when the chip clings to the shoe along the shank by fibers of unsevered leather.

An important feature of the present invention consists in improved means for seizing the chip which has been completely or partially severed by the breasting knife and removing it from the shoe. The chip removing means preferably moves toward and from the shoe with the breasting knife. One of the members between which the chip is seized and held and which is operated to remove the chip from the shoe may conveniently be the knife itself, another mem-

ber being provided to hold the chip against the knife during its return stroke and causing the chip to be removed from the shoe. Machines of this type are usually provided with a shank stop or bunter which comes in contact with the shank of the shoe during the operation of the knife and coöperates with means for arresting the stroke of the knife. The shank stop or bunter may conveniently be employed as the member which coöperates with the knife to seize and hold the chip during the return stroke of the knife. In the construction shown the end of the shank stop is forced against the heel breast prior to the completion of the breasting cut and is held there during the remainder of the cutting and during the return of the knife. In the construction shown the end of the shank stop is extended laterally to form a foot. The face which is next the heel is inclined away from the breast so that the lower rear edge of the foot engages the heel breast adjacent to the shank, thereby clamping the chip against the beveled edge portion of the knife at the bottom of the chip, and insuring its complete removal. The foot is formed to engage the chip close to the side portions of the shank and by reason of this formation and because of the concave form of the knife it bears upon the chip most forcibly adjacent to the corners of the heel breast where the chip is most likely to cling to the shank, and, therefore, insures the removal of the parts of the chip adjacent to the edges of the shank and avoids separation of the layers which compose the chip, as might occur if the chip were not seized along its lower edge.

Another feature of the invention consists in improved means for releasing the chip from the chip removing means. In the construction shown this is effected by movement of the work support. As the work support is swung outwardly for the removal of the shoe means is operated for moving the foot away from the knife to release the chip, and at the same time means is operated to unlock the foot from its carrier member, permitting it to drop to normal position. The dropping of the foot insures that the chip will be shaken

off of the foot if it should show any tendency to cling thereto.

Another feature of the invention consists in means for directing the chip after it is released by the chip removing means. This may comprise, as shown, a chute which is attached to the jack post and which, by movement of the jack outwardly to release the chip, is carried into position under the chip removing mechanism to receive the chip when dropped, and directs the chip into a suitable receptacle.

Another feature of the invention is found in the construction of the foot of the shank stop. This foot is provided with bearing surfaces at its lateral ends only so that it engages the sides or marginal portions of the shank, and the pressure which is applied to the foot, therefore, tends to bend the sole 20 transversely and bring the shank portion of the sole against the wood of the last. This is of importance as the knife edge has a concavity corresponding to the transverse curve of the last at the shank, and hence corresponds to the curve of the shank portion of 25 the sole when the sole is made to conform to the last. The shank, however, has a tendency to be more nearly flat than the last, and hence the knife may cut into the shank at the 30 sides before it severs the chip at the center. Hence, the shank should be firmly held to the last at the side portions during the breast- 35 ing operation. In some shoes, especially women's, the shank stiffener forms a ridge down the central portion of the shank, and the shank stiffener is not always uniformly placed in different shoes. The foot described straddles the stiffener and bears upon the 40 sole at each side thereof, so that its action is not affected by the presence of the shank stiffener or by slight displacement of the 45 stiffener. This form of foot is well adapted also for breasting shoes which have a shank molded with oppositely inclined side por- 50 tions which meet to form a ridge extending longitudinally of the shank. This is known as the "cottage roof" shank. Furthermore, the foot is preferably mounted upon an axis extending lengthwise of the shoe so that it 55 may rock laterally to accommodate itself to the lateral inclination of the shank of the shoe and equalize the pressure upon the two sides of the shank. In the construction shown means is provided also for increasing 60 the pressure of the foot against the shank just prior to the completion of the breasting cut to insure that the shank portion of the sole will be brought firmly against the last. This means may comprise a spring, the ten- 65 sion of which is applied to the foot prior to the tripping of the knife to discontinue its cutting action.

Another feature of the invention consists in novel means for positioning and holding

the shoe for the operation of the knife. In 65 the construction shown two fingers, which are preferably connected together for equal and opposite swinging movement, are mounted under the plate of the machine which engages the tread face of the heel and 70 which is commonly called the presser plate or tread plate. The fingers extend from the rear forwardly to embrace the heel and preferably are provided at their front ends with hooks which are adapted to engage the 75 corners of the heel breast, or the breast corners of the top lift, and to limit the forward longitudinal movement of the heel and shoe, thereby determining the amount to be removed from the heel by the breasting 80 knife. Mechanism is provided for separating the fingers to disengage them from the heel and to then retract the fingers out of the path of the breasting knife and also to lock them in retracted position until the shoe is 85 removed from the machine. The fingers have a normal degree of separation substantially equal to the width of the heel, and an adjustment is provided to vary the normal separation of the fingers to correspond to the 90 width of the heel being treated. An adjustment is also provided to vary the positions of the fingers longitudinally of the heel so that a greater or less amount of material may be removed from the breast end of the 95 heel. Furthermore, in the construction embodying the present invention this adjustment may be effected without disturbing in any way the operation of the mechanism for separating and retracting the fingers. 100

Another feature of the invention consists in shoe supporting and holding means which comprises a tread plate, a resiliently supported last post which may be moved into and out of position beneath the tread plate, 105 means for locking the post against downward movement, which is effective when the post is in position beneath the tread plate, and means for applying pressure to the tread plate to clamp the shoe against the 110 post. This construction enables the operator to position the shoe on the support and then press the shoe down sufficiently to permit it to swing beneath the tread plate. The shoe is then released and rises until the tread face 115 of the heel engages the tread plate, the shoe being then locked against downward movement.

Another feature of the invention consists in the combination with the positioning fingers of shoe supporting and holding means which comprises a tread plate, a depressible post or spindle which is held against depression to support the last when the heel of a shoe is positioned against the tread plate, and means for applying pressure to the tread plate. The shoe is placed upon the supporting post, depressed, and swung into 125

position beneath the tread plate. When thus positioned and released the heel rises between the positioning fingers and against the tread plate and the post is locked against depression. The heel is now held under light pressure against the tread plate and is drawn forward to bring the corners of the heel breast into contact with the positioning fingers which determine the amount to be removed from the heel. When the machine is started pressure, which is created by power operation of the machine, is caused to press the tread plate firmly against the heel.

Another important feature of the invention consists in novel means for holding the knife and particularly in means for holding to shape or shaping a thin, flexible knife which is not rigid enough of itself to withstand, without bending, the required cutting operation. This means may comprise a member having a surface which supports a substantial portion of a face of the knife, preferably its front face which is usually concave, and means for clamping together the marginal portions of the knife and member to hold the knife to the member. The knife may with advantage have a curvature which differs from that of the member, so that the clamping means will shape the knife to the member, which then becomes a forming member. Usually the curvature of the forming member will be greater than that of the knife, but in case a flat knife is required the forming member will be flat while the knife itself will be given a slight curvature, so that when the knife and the forming member are clamped together along their margins the knife will be straightened, and the engaging surfaces of the knife and forming member will be held firmly in contact.

Another feature of the invention consists in means for absorbing or storing up the energy due to the momentum of the moving parts of the knife operating mechanism during their upward or idle stroke and for utilizing that energy during the succeeding or operative stroke to apply pressure to the work clamping and holding means. As shown, the work holding means comprises a tread plate having a roughened lower face to engage the tread face of the heel, and a work support which is held against depression and sustains the work to withstand the pressure of the plate. A portion of the energy stored may, as in the construction shown, be utilized to overcome the inertia of the knife carrier and connected parts during the first part of the operating stroke, and the remainder of the energy may be caused to apply clamping pressure to the work.

These and other features of the invention, including more important details of construction and combination of parts, will ap-

pear more fully from the following detailed description when read in connection with the accompanying drawings, and will be pointed out in the appended claims.

Figure 1 is a side elevation of the machine;

Fig. 2 is a detail view, partly in section, of a portion of the work support;

Fig. 2^a is a detail of a modified form of the last support;

Fig. 3 is a side elevation of the work positioning fingers and their adjusting and operating mechanism;

Fig. 4 is a view of Fig. 3 taken from below;

Fig. 5 is a detail in perspective of the mechanism for tripping the fingers to permit their return to operative position;

Fig. 6 is a sectional detail plan view from below, on the line 6—6, Fig. 3;

Fig. 7 is a front view of the upper part of the machine;

Fig. 8 is a sectional view of a knife holding mechanism on the line 8—8 of Fig. 7, some of the parts being omitted;

Fig. 9 is a vertical section showing the chip removing mechanism; and

Fig. 10 is a section on the line 10—10 of Fig. 7.

The working parts of the machine are supported on a frame or column 2, Fig. 1, near the base of which is pivoted at 4 a jack post 6. An upper extension 8 of the jack post is telescoped in the lower part 6 and is splined therein to prevent relative rotation of the parts. The extension 8 is threaded through a hand wheel 10 by which the length of the jack post may be adjusted. To the upper end of the extension 8 is clamped, by a screw 11, a casting 12 which has a forwardly and upwardly extending portion 14 for supporting a toe rest 16. A rod 20, Fig. 2, is mounted for longitudinal movement in the casting 12. The rod carries at its upper end a last pin 22 which enters the thimble of the last during the operation of the machine upon a shoe. The rod 20 is resiliently upheld by a comparatively light spring 24 of sufficient strength to support the parts resting thereon, together with the weight of the last and shoe. The spring, however, is light enough to permit the shoe to be readily depressed by pressure of the hand upon it. Rotation of the rod 20 is prevented by a screw 26 which engages a suitable longitudinal groove in the rod. To enable the upper of a shoe to be readily slipped over the last pin 22 and the upper portion of a last support, resilient leaves or plates 23 are attached to the casting 12 and extend upward nearly to the normal level of the crown of the last. These plates prevent the edges of the upper from catching on the projecting parts or between the crown of the

last and crown engaging surface upon the last support. On the front face of the rod 20 teeth 28 are formed which coöperate with a pawl block 30 movably mounted on one 5 arm 32 of a bell crank lever which is pivoted at 34 to the casting 12. The pawl block 30 is held normally in engagement with the teeth 28 by a leaf spring 36. To receive the shoe the jack post is swung outwardly into 10 an inclined position about the center 4, the last being rested upon the upper end of the rod 20 with the forepart resting on the toe rest 16, which is vertically and horizontally adjustable, as shown, properly to receive it. 15 In the shoe receiving position of the jack post, the lower arm 38 of the bell-crank carrying a roll 40 engages the high outer portion of a cam bar 42 pivoted at 44 to an adjustable bracket 46 on the machine frame 20 and riding on a roll 48 mounted on the casting 12. Upon movement of the jack outwardly the roll 40 is raised sufficiently by the high part of the cam bar 42 to throw the pawl block 30 out of engagement with 25 the teeth 28 and leave the rod 20 free to be moved downwardly against the spring 24, when the operator positions the shoe and presses down upon it. He then swings the jack backwardly to bring the shoe under the 30 knife and the tread face of the heel under a tread plate 50 which has initially a predetermined vertical position. The shoe is then released by the operator and the spring 24 raises the shoe against the tread plate 35 30. The described movement of the shoe and the jack has meantime carried the roll 40 off of the high part of the cam bar 42 so that the bell-crank lever 32, 38 and pawl 30 may respond to the spring 36, which 40 forces the pawl into locking engagement with the teeth formed on the rod 20 as shown in Fig. 2. This effects the locking of the shoe vertically against the pressure of the tread plate which operates in a manner to be described to apply pressure to the 45 shoe.

The amount of inward swinging movement of the jack post is determined by an adjustable limiting stop 27 threaded into 50 a downward projection of the jack post 6 below its pivot 4 which contacts with one wall of a recess 29 in the base of the frame 2. A similar stop 31 may be provided on the other side of the projection to limit the 55 outward swinging of the jack post. In the construction embodying this invention means is provided for insuring that the jack post shall swing to the limit of its inward movement against the stop 27. This comprises 60 a cylinder 33 pivoted at 25 to the jack post and having therein a plunger 35 and a stiff spring 37 which forces the plunger 35 outwardly. The end of the plunger is formed to engage a stationary pin 39 on the frame 65 2 which is positioned in line with the pivot

25 and the pivot 4 of the jack post when the jack is in a neutral position partially withdrawn from operative position. Therefore, when the jack post is in this position the spring in the cylinder 33 will be compressed, 70 and when the jack is moved inwardly beyond this position the spring 37 will re-act against the stationary pin 39 to push the post inwardly as far as permitted by the stud 27. When moved outwardly beyond 75 this position the jack post will be similarly forced against the stop 31. This construction is particularly useful in connection with the form of last support shown in Fig. 2^a, in which the rod 20, instead of having thereon the last pin 22 and the plates 23 as shown in Fig. 1, is provided with a cap 41 which is bored to receive the end of the rod 20, the upper surface of the cap 41 being at the same vertical height as the surface at the 80 base of the last pin 22 which engages the crown of the last. With this construction the crown of the last is rested upon the upper surface of the cap 41, and the toe portion of the shoe upon the rest 16. The 85 shoe and jack are then swung in far enough so that the cap 41 will support the last at the rear portion of the crown, the spring plunger 33, 35 insuring that the surface of the last supporting cap 41 will be positioned 90 uniformly for every last.

The tread plate 50 which engages the tread face of the top lift of a heel is detachably mounted on a block 52. The front edge 53 of the plate (Fig. 4) is contoured to correspond with the curvature to be given to the heel breast and to the curvature of a knife 71 and may be removed and replaced with another of different curvature as required. The plate 50 is held upon the block 100 by headed studs 54 which engage a suitable T-slot in the block 52 and permit the plate to be removed by movement to the right in Fig. 3. The plate 50 is retained in operative position in the block by a spring pin 56 105 having a handle 58 which operates over a cammed surface to withdraw the pin when the pin is rotated by the handle 58 (Fig. 3). The block 52 which carries the tread plate 50 is mounted on a slide 60 for angular 110 adjustment about a pivot 62. This adjustment is effected by a screw 64 (Fig. 3) which engages an upstanding projection 51 on the block 52. The projection 51 is held yieldingly in contact with the screw 64 by a 115 spring plunger 57 having a tapered end arranged to engage the upper side of a lug 55 on the slide 60. The front end of the slide may be thrown downwardly about the pivot 62 to facilitate the removal of the plate 50 120 without interference with the knife 71, whereupon the plunger 57 will engage the lower side of the lug 55 and hold the block 52 in that position. The slide 60 is linked at its upper end at 61 to the mid-portion 125 130

of a lever 66, Fig. 7, which is pivoted at one end to a bracket 68 on the machine frame while the other end is acted upon by a stiff spring 70 mounted in corresponding recesses in the lever 66 and in a bracket 72 secured to the machine frame. The tension of the spring 70 may be adjusted by a screw 74 acting on a plate 75 against which the spring abuts.

10 The machine is provided with an actuating slide 80 which reciprocates vertically in the frame and which, as it approaches its upper limit of movement, engages an adjustable abutment 82 on the lever 66, thereby 75 raising the lever and compressing the spring 70. As the slide 80 moves downwardly the spring actuates the lever 66 to force the tread plate 50, by the slide 60, firmly against the tread face of the heel of a shoe 20 which is rigidly supported on the jack as described. To prevent excessive movement of the lever 66 when no shoe is in the machine, an extension 65 of the lever 66 is provided which contacts with the frame of the 25 machine.

The slide 80 is reciprocated vertically by power applied to a fly wheel 73 which is connected upon depression of a treadle 76 with a one-revolution clutch of known type, as 30 shown in Fig. 1, to operate a crank 77. A connecting rod 78 communicates motion from the crank 77 to the slide 80. The machine normally comes to rest, as shown, with the slide 80 elevated and the crank therefor 35 on its upper dead center, the spring 70 being then compressed. When the clutch is thrown in to start the machine the crank passes from its position of dead center, and the spring acts to impart to the slide an accelerated movement until the tread plate 40 engages the heel. This action of the spring quickly overcomes the inertia of the parts and results in a quicker and more effective cutting action of the knife 71 which is actuated by it. Furthermore, after the operative stroke of the knife is effected, the 45 slide 80 is raised against the tension of the spring 70 which tends to overcome the momentum of the moving parts and bring 50 the machine quickly to rest without undue strain on the stopping mechanism. It will be understood that, as is usual in machines of this type, the knife slide 81 is mounted for movement parallel to the actuating slide 55 80, the slides being normally locked together. The actuating slide carries the knife slide downwardly to effect the breast- 60 ing operation, and when the breasting cut is completed the knife slide 81 is automatically disconnected from the actuating slide 65 80 which completes its stroke idly and upon its return picks up the knife slide 81 by coming in contact with an overhanging projection 85 and brings it back to raised position.

The novel devices with which the machine is provided to coöperate with the shoe support and the tread plate to position the work will now be described. Fig. 4 is a view of the under side of the tread plate 50, showing 70 positioning fingers 83, 84 which are pivoted at 77, 78 to a slide 86 which is mounted in the block 52 for movement longitudinally of the shoe independently of the plate 50. The slide is resiliently held forwardly, or toward the right, Fig. 3, by a tension spring 87 mounted between pins which are respectively on the slide 86 and on the block 52. The forward position of the fingers is adjusted by a thumb screw 88 20 80 which is threaded through a depending lug 89 on the slide 86 and abuts against a depending lug 90 on the block 52. The lug 90 passes through a suitable opening or slot in the slide 86. The screw 88 is held frictionally against accidental movement in the lug 89 by a clamp screw 92. The fingers 83, 84 are connected together for equal and opposite movement by interengaging toothed segments at 94. The fingers are held toward 90 each other by a spring 96 and the normal position of the fingers, that is, their degree of separation, may be adjusted by a thumb head 98.

The thumb head 98 is on a screw 100 95 100 which is rotatably mounted in brackets 102, 103 and has right and left threaded engagement respectively with members 104, 105. The members 104, 105 are free to swing on the screw 100 and the friction of the screw in the members may be adjusted by the clamp screws 106, 107. The upper ends of the members 104, 105 have inwardly inclined faces 108, 109, Figs. 4 and 6, which engage correspondingly inclined faces on 105 projections 111, 113 on the fingers 83, 84. The engagement of these inclined faces limits the approaching or closing movement of the fingers, and the amount of normal separation of the fingers may be varied by 110 turning the head 98 to move the members 104, 105 toward and from each other laterally carrying with them the fingers.

The knife during its breasting stroke passes close to the curved front edge 53 115 of the plate 50, Fig. 4, and since the fingers 83, 84 project beyond the front edge of the plate 50 to position the heel for the breasting operation they must be first separated to release their hooked ends from the side 120 edges of the breast of the top lift and must then be withdrawn rearwardly out of the path of the knife. Referring again to Fig. 3 the slide which carries the breasting knife is provided with a cam projection 115 which 125 during the downward stroke of the slide engages a cam roll on an arm 110 of a rock shaft pivoted at 112 and having another arm 114 which extends downwardly into position to engage a screw 116. The screw 130

116 is threaded through a member 118 which is mounted to turn on the screw 100 between the brackets 102, 103. The screw 100 is held from movement longitudinally in this member by a dog 120, Figs. 4 and 7 having a tail which engages a groove in the mid portion of the screw 100. The dog is held in place by a screw 127 and a pin 129. The member 118 is T-shaped and its lateral extensions engage the members 104, 105. The arm 114 is moved rearwardly by engagement of the cam projection 115 upon descent of the knife slide and before the knife engages the work and the arm 114 is moved rearwardly against the screw 116, thus rocking the member 118 about the screw 100 as an axis. The lateral projections of the member 118 engage the members 104, 105 and rock them about the same axis (screw 100) bringing the inclined faces 108, 109 on their upper ends against the corresponding inclined faces on projections 111, 113 on the fingers 83, 84. These inclined faces coöperate to separate the forward ends of the fingers against the spring 96 to free the hooked forward ends of the fingers from the heel, and continued rocking movement of the members 104, 105 by the same means brings the lateral projections 117, 119 of the members 104, 105 against the square front faces of the projections 111, 113 on the fingers, Fig. 6, and moves the fingers and the slide 86 bodily backward against the spring 87 out of the path of the knife. The fingers are held in proper position against the lower face of the tread plate 50 by clips 131, 133 secured by screws to the lower face of the block 52. When the slide 86 is adjusted by means of the screw 88 it is necessary to maintain the screw 116 in operative relation to the arm 114. Simultaneous adjustment of the screws 88 and 116 is effected by means of a square rod 122 which is held by a pin 123 in the end of the screw 88 and engages loosely a square hole in the screw 116, the hole being large enough to permit the rocking movement of the member 118, but not large enough to permit relative rotation of the rod 122 and the screw 116.

To facilitate the removal of the shoe after the operation of the breasting knife it is desirable that the fingers remain in retracted position after the knife slide has returned to normal position. To effect this a locking member or lever 124 is pivoted upon a shaft 126 mounted in ears on the block 52. One end of the lever is widened and is held against the screw 88 by a spring 128 wrapped around the hub 125 of the lever 124 and arranged to press the widened end upwardly. As the screw 88 is moved backwardly by the rearward movement of the fingers and slide 86 the end of the lever 124 assumes a position between the end of the

screw 88 and the lug 90 against the rod 122 and prevents forward movement of the slide 86 due to tension of the spring 87 when the knife slide has returned to normal position.

When the jack and shoe have been swung out from under the tread plate for the removal of the shoe it is desirable to have the positioning fingers 83, 84 brought again into position for operation upon the next shoe. In the construction shown this is effected automatically by mechanism shown in Figs. 1, 3 and 4. The jack post 6 carries a rearwardly projecting arm 130 to which is pivoted a rod 132. The rod 132 is pivoted at its upper end to one arm 134 of a rock shaft pivoted at 136. When the jack post 6 is swung outwardly of the machine for the removal of the shoe the rod 132 is given a substantially vertical movement upwardly and this movement is utilized to trip the locking lever 124 to remove its end from between the end of the screw 88 and the lug 90 and permit the slide 86 and the fingers 83, 84 to move forward under the impulse of the spring 87 into operative position. This is effected by a block 140 adjustably clamped by a screw 142 to the rod 132 and arranged to engage and lift the offset end of the lever 124, Figs. 4 and 5.

The mechanism for removing from the work the chip which is wholly or partially detached by the breasting knife will now be described. Machines of this type are usually provided with mechanism comprising a shank stop or bunter which contacts with the shoe at the shank and coöperates with mechanism for arresting the movement of the knife to prevent its cutting into the shank. This member comprises, in the machine embodying the present invention, a foot 150 which engages the shank of the shoe. The foot 150 is mounted on a horizontal stud 152 projecting lengthwise of the shoe from the member 150. The foot may, therefore, rock laterally to accommodate itself to the lateral inclination of the shank of the shoe. The shoe engaging face of the foot 150 is arched and has its central portion removed to form a recess. The recess accommodates the ridge on the shank formed by the shank stiffener or the angular portion of a "cottage roof" shank and bears only on the marginal portions of the shank. The member 154 slides vertically in a T-slot in a member 160 which is pivoted at 162 to the reciprocating knife carrying slide 81 of the machine. A spring plunger 166, Fig. 9, bears on the end face of the member 160 at a point forward of the pivot 162, and therefore the plunger 166, under the impulse of a spring 170, forces the foot 150 toward the breast of the heel. The movement of the plunger 166 may be controlled by a nut 172 so that the foot 150 will not come into actual contact with the knife when there is

no chip between them, and to prevent excessive movement of the member 160 when no knife is in the machine. The nut 172 is held from accidental rotation by a cotter 5 pin 171 passing through the nut and a slot in the stem of the plunger 166. Rotation of the plunger relatively to its socket is prevented by a pin 173 passing through the same slot.

10 Supposing a shoe to be in the machine with the tread face of its heel against the plate 50 and the knife carrying head 81 and knife 71 and connected parts to be approaching the shoe,—after the tread plate has been 15 forced against the tread face of the heel as above described the foot 150 engages the shank of the shoe and the member 154 is pushed up into the member 160 until a projection 182 from the member 154, Fig. 7, 20 engages a pivoted latch 184 which by engaging a projection 186 on the sleeve 160 holds the stop foot 150 back against the pressure of the spring plunger 166. As the latch is moved by the projection 182 from 25 a stop pin 183 about its pivot 187 on the knife slide 81 against a spring 188, the projection 186 is freed from the latch 184 and the foot swings forward against the breast of the heel and clamps the chip against the 30 knife. As the cutting operation of the knife progresses, the member 154 is pushed into the sleeve 160 until a spring operated catch 190 pivoted at 191 engages a notch 193 in the member 154 and locks it in elevated position. When the knife is about to complete the cut, a screw 192 on a trip lever 194 comes against a projection 195 on the member 154 whereby the trip lever 192 is raised against a stiff spring 196 which 40 crowds the foot 150 hard against the shank and forces it against the last prior to the tripping of the knife to arrest its cutting movement. Finally when the knife has reached the surface of the shank, the adjustment of the screw 192 is such that the trip lever 194 is operated sufficiently to disconnect the knife carrier 81 from the actuating slide 80 in a manner well-known and upon the return of the actuating means the 45 knife is carried upwardly therewith and the foot 150, being locked with it, also rises carrying up the chip held between the knife and the foot. When the machine stops, the jack post with the shoe thereon is drawn 50 forwardly. This movement pushes upwardly on the rod 132 (Fig. 1) which is connected with an arm 134 of a rock shaft pivoted at 136 to the frame of the machine and having another arm 200 which carries 55 a rod 204 having a lost motion connection at 203 with a lever 208 pivoted at 210 and having a downwardly projecting segmental portion 212 which is arranged to engage the catch 190 which holds the member 154 elevated. The lever 208 is also provided with

an arm 211 which engages a projection 213 on the member 160 to the right of its pivot 162. As the jack is swung out the rod 204 is moved to the limit of its lost motion connection with the lever 208 and then 70 moves the lever. This causes the arm 211 to press on the projection 213 and swing the member 160, and of course the foot 150, away from the shoe, and at the same time causes the wedge shaped end of the segmental portion 212 to engage a beveled portion of the catch 190 and swing it free of the notch 193 to permit the member 154 to drop. This, of course, releases the chip 75 which falls into a chute 214 mounted upon the jack post to swing therewith by means of a strap 215 secured to the chute and held upon the jack by the clamp screw 11. The chute 214 directs the chip so that it falls inside the ring 217 which is provided with 80 inwardly directed spurs 219 upon which a bag may be hung to receive the chips. The bag is shown in dotted lines in Fig. 1.

In order to change the knives of the machine conveniently it is desirable to have the 90 member 160 and connected parts readily movable out of operative position. This is effected, as shown in Fig. 9, by so arranging the parts that the member 160 and connected parts may be swung to the right 95 about 162 as a center, the spring plunger 166 passing from the flat top portion of the member 160 on to a portion 221 concentric with the axis 162, and finally as the member 160 assumes a substantially horizontal position, engaging a depression 223 and holding the member yieldingly in that position. When the member 160 and its connected parts is swung back into operative position the projection 195 must be brought into 100 proper position beneath the screw 192 on the trip lever 194, for if it is not so positioned and the machine be operated the shoe will be cut through the shank and spoiled. It is accordingly desirable to provide means 105 for preventing the members 160 and 154 from being wrongly positioned accidentally when brought back from their inoperative position. This is effected by extending downwardly the projection 211 which tips 110 the member 160 to release the chip so that the extension will be in the way of the projection 182 unless the member 154 is positioned vertically so that the projection 195 115 will pass under the screw 192.

The novel knife and knife holding mechanism are best shown in Figs. 7 and 8. The knife 71 used in this machine may be a thin blade, of say $\frac{3}{16}$ to $\frac{1}{8}$ of an inch in thickness, having a uniform temper throughout 125 and having a given curvature which is preferably somewhat less than that required for the knife when in operation. Co-operating with this thin blade which is the actual cutting member is a front plate 252. This

plate has the exact curvature which it is desired that the knife shall have. The knife 71 and the plate 252 are held by their side edges in grooved clamping members 254, 256 which extend substantially the length of the longest knife to be used. The members 254, 256 are moved toward and from each other by a hand wheel 258 which rotates a right and left hand worm 260 meshing with worm pinions 262 fixed to vertical shafts 264, 266. These shafts each carry two pinions 268, which mesh with upper and lower racks 270 formed in the clamping members 254, 256. The clamping members 254, 256, move, as shown in Fig. 7, in right line paths laterally of the knife.

It will be clear that by rotating the hand wheel 258 the side clamping members or jaws 254, 256 will be moved simultaneously toward and from each other and may be firmly clamped against a knife held between them, as shown in Fig. 8. From this figure it will also appear that grooves 255, 257 in the clamping members are so shaped relatively to the forming plate 252 and knife 71 that the knife 71 will be bent to the form of the plate and firmly held against it. The knife 71 is a little narrower than the former 252, and the edges of the former are inclined to correspond to the engaging faces of the grooves 255, 257 so that as the clamping members are forced inwardly the former 252 will force the knife 71 against the rear outer corners of the grooves and flex the knife to the shape of the former if the knife has a less curvature than the former and therefore tends to stand away from the former at its side edges.

The former 252 has a vertical slot 280 open at its upper end to accommodate a knife abutment 282, best shown in Fig. 9. The abutment is on a stem 284 which may be adjusted vertically and as the knife is ground away and becomes shorter the abutment may enter the slot 280. To hold the stem in adjusted position a ball clutch is provided comprising an upstanding tube 286 on the knife carrier 81 through which the stem 284 slides, and to which is threaded a cap 288 having an inclined surface 290 with which balls 292 engage. It will be seen that by screwing down the cap the balls 292 will become wedged by the surface 290 against the stem 284 and that any upward pressure on the stem will only tend to wedge the balls more tightly, thereby holding the stem firmly in adjusted position but permitting adjustment thereof for knives of different lengths.

60 A lug 296 is provided in one of the knife grooves on which one corner of the knife edge may rest to determine the position of its lower edge which is always the same, the abutment being adjusted down into bearing

with the upper end of the knife, whatever its length. A similar lug may be provided to engage a notch 251 in the side of the member 252 which is always the same length. By these two lugs the parts 71 and 252 may be easily located relatively to 70 the jaws 254, 256 and relatively to each other before the jaws are closed to hold them firmly together.

Although the operation of the various groups of mechanism has been given in connection with the description thereof, it may facilitate the understanding of the operation, as a whole, of the illustrative machine shown in the drawings to review in proper sequence the steps involved in breasting the 80 heel of a shoe thereon.

Referring to Fig. 1, the jack 6 is first swung outwardly as far as the stop 31 permits, a shoe is then placed upon the jack, the last pin 22 engaging the thimble of the last, or, in case the support shown in Fig. 2^a is used, the crown of the last resting upon the cap 41. The toe portion of the shoe is supported upon the toe rest 16 which is adjusted to bring the plane of the tread 90 face of the heel parallel with the tread plate 50, the latter being adjusted at the proper angle to the horizontal to give the desired angle to the heel breast. The rear portion of the shoe is depressed by the operator against the spring 24, and the jack is swung backward. During this backward movement the spring plunger 35 assists the operator in moving the jack against the limiting stop 27. As the jack swings backward the roll 40 passes off of the high part of the cam 42, and the pawl 30 engages the teeth 28 and prevents further depression of the shoe, although upward movement thereof is still permitted. The shoe is now allowed to rise under the impulse of the spring 24 between the fingers 83, 84 against the tread plate 50, the fingers 83, 84 being adjusted by the thumb head 98 to the proper distance apart to admit between them a heel of the width being breasted. The shoe is then drawn forward to bring the breast corners of the heel against the hooked ends of the fingers 83, 84, which limit the forward movement of the shoe. The thumb head of the screw 88 is adjusted to move the fingers longitudinally of the shoe so that the proper amount will be removed from the heel by the knife, the position of the knife cut on the heel being indicated by 115 the edge 53 of the plate 50.

The operator now steps on the treadle 76 to throw in the clutch for the power operation of the machine. As the crank 77 moves beyond the dead center the spring 70 acts 125 initially to overcome the inertia of the actuator 80 and knife carrier 81 until the tread plate comes into firm bearing on the

heel, whereupon the energy stored in the spring 70 holds the heel firmly against the work support which is now rigidly upheld by the pawl 30. The cam 115 on the knife 5 carrier comes in contact with the cam roll on the arm 110 and operates the arm 114 to open and retract the positioning fingers 83, 84 out of the path of the knife. The foot 150 on the member 154 comes in contact with the shank of the shoe, and the member 154 telescopes into the member 160 until the projection 182 contacts with the latch 184 and lifts it from behind the projection 186. This permits the foot 150 and 10 connected parts to swing toward the heel about the center 162 under the impulse of the spring plunger 166 and the foot to press the chip against the knife which is now nearly through the heel. The adjusting 15 screw 192 on the trip lever 194 finally engages the projection 195, and the end of the trip lever is held from movement relatively to the knife slide, causing the spring 196 to act on the foot 150 and press the sole firmly 20 25 in contact with the shank portion of the last until finally, when the edge of the knife has reached the shank, the knife slide 81 is disconnected from its actuator 80, which completes its downward stroke idly and on its 30 return encounters the projection 85 and carries the knife carrier back to normal position assisted by the spring 290, Fig. 1. During the latter part of this stroke the slide 35 encounters the abutment 82 and has its momentum absorbed by the spring 70. Meantime the chip has been held between the forming plate 252 of the knife 71 and the foot 150, which has been locked against downward movement relatively to the knife 40 45 by the catch 190 which engages one of the notches 193 and has been carried upward by the knife and foot and then returned. The fingers 83, 84 are locked in their retracted position by the engagement of the end of the lever 124 between the end of the 50 55 screw and the lug 90. The jack is now swung outwardly and as the shoe clears the tread plate the block 140 on the rod 132 operates the lever 124 to release the fingers 83, 84 and permit them to return to operative position under the influence of the spring 87. The rod 132 also operates through the rod 204 to move the lever 208 which acts through the projection 211 to 60 65 swing the member 160 away from the presser foot 150 to release the chip, and at the same time the end of the segmental portion 212 of the lever 208 engages the latch 190 and releases the member 154 which drops with the foot 150, thereby further increasing the space between the foot 150 and the knife and insuring that the chip will be disengaged and will fall into the chute 214 which 70 75 has been swung beneath it by the outward

movement of the jack. The chip falls into 65 the bag held by the ring 270, and the parts are now in position for operation upon the next shoe.

Having thus described the invention, what is claimed as new and desired to be secured 70 by Letters Patent of the United States is:—

1. In a machine of the class described, the combination of a knife, means for operating the knife to cut off a chip from the work, and means acting automatically upon contact with the work to seize and remove the chip cut off by the knife. 75

2. In a machine of the class described, the combination of a reciprocating knife, and means rendered operative by contact with 80 the work to seize the chip cut off by the knife and acting during the return movement of the knife to remove the chip. 85

3. A machine of the class described having, in combination, a reciprocating knife, 85 tensioned resilient means released automatically upon downward movement of the knife to clamp the chip against the knife during its return stroke, and means for retensioning the resilient means. 90

4. In a machine of the class described, the combination of a reciprocating knife acting to cut a chip from the work, means for effecting removal of the chip operated by the movement of the knife, and means operated 95 by movement of the work for releasing the chip. 100

5. In a machine of the class described, the combination of a reciprocating knife constructed and arranged to cut a chip from 100 the breast of a heel, and means for forcing the chip against the knife during the return movement of the knife formed to press and hold the chip against the knife entirely by pressure applied perpendicular to the knife 105 and most forcibly at the corners of the heel breast. 110

6. In a machine of the class described, the combination of a knife, means for reciprocating the knife toward and from the work, 110 a chip remover, means becoming effective upon movement of the knife toward the work for causing the remover to grip the chip against the knife and hold it there during the movement of the knife away from 115 the work, and means for releasing the chip only after the work is removed from beneath the knife. 120

7. In a heel breasting machine, the combination of a breasting knife movable toward and from the shoe, and means, partaking of the movement of the knife and rendered effective by contact with the shoe, for seizing the chip, and means for operating the seizing means to remove the chip from 125 the shoe. 125

8. In a heel breasting machine, the combination of a breasting knife movable to-

ward and from the shoe, and means, partaking of the movement of the knife and rendered effective by contact with the shoe, for seizing the chip, means for operating the seizing means to remove the chip from the shoe, and means for releasing the chip from the seizing means.

9. In a heel breasting machine, the combination of a shoe support, breasting means movable toward and from the shoe support, and means, partaking of the movement of the knife and rendered effective by contact with the shoe on said support, for seizing the chip, and means for operating the seizing means to remove the chip from the shoe.

10. In a machine of the class described, the combination of a work support, a knife movable toward and from the work support, means for seizing and removing the chip operated by movement of the knife, and means, operated by movement of the work support, for releasing the chip.

11. In a machine of the class described, the combination of a work support, a knife movable toward and from the work support, means for seizing and removing the chip operated by movement of the knife, and means, operated by movement of the work support, for resetting the chip seizing means in normal position.

12. In a machine of the class described, the combination of a reciprocating knife, a stop arranged to engage the shank of the shoe, means operatively connected with the stop to arrest movement of the knife when the shank is reached, and means to press the stop toward the knife to hold the chip against the knife during the return movement of the knife.

13. In a machine of the class described, the combination of a reciprocating knife, a foot mounted for movement with the knife and for movement relatively thereto having a normal position in advance of the knife, means for forcing the foot toward the knife to clamp the chip cut off by the knife, means operatively connected with the foot to arrest movement of the knife when the shank is reached by the knife, and means for holding the foot against movement relatively to the knife during the return stroke of the knife.

14. In a machine of the class described, the combination of a vertically reciprocating knife, chip holding means mounted for movement with the knife and also independently thereof and having a normal position in advance of the knife, means acting upon reciprocation of the knife to force the chip holding means toward the knife, said chip holding means being moved to a position adjacent to the knife edge by contact with the shoe, and means for maintaining the chip holding means in holding relation to the knife during the return of the knife.

15. In a machine of the class described,

the combination of a vertically reciprocating knife, chip holding means mounted for movement with the knife and also for movement independently thereof and having a normal position in advance of the knife, said chip holding means being arrested by contact with the shoe and brought to a position adjacent to the knife edge, means rendered effective by the arrestment of the chip holding means to force the chip holding means toward the knife and to maintain the chip holding means in holding relation to the knife during the return of the knife, and means for releasing the chip prior to the next operation of the machine.

16. In a machine of the class described, the combination of a reciprocating knife, a stop, means for forcing the stop toward the knife, means for locking the stop in a position away from the knife in opposition to said means, and means operating during the descent of the knife to release the locking means and permit the stop to clamp the chip against the knife.

17. In a machine of the class described, the combination with a reciprocating knife, of a chip remover, means becoming effective upon movement of the knife for causing the remover to grip the chip against the knife, and means operable after the work is withdrawn from beneath the chip for releasing the chip.

18. In a heel breasting machine, the combination of a work support, heel breasting and chip removing means movable toward and from the work support, and chip receiving means movable by the work support beneath the chip removing means.

19. In a heel breasting machine, the combination of a work support, heel breasting and chip removing means movable toward and from the work support, chip receiving means movable by the work support beneath the chip receiving means, and means, operated by the work support, for releasing the chip and permitting it to fall into the receiving means.

20. In a machine of the class described, the combination of a reciprocating knife, a chip remover formed to engage the chip in the angle between the breast and the shank and constructed and arranged for rocking movement for equalizing the bearing of the remover upon the shank, means for holding the remover toward the knife edge, and means for retracting the knife and the remover together.

21. In a machine of the class described, the combination of a reciprocating knife, a chip remover arranged to engage the chip on the heel breast and having an inclined chip engaging face and lateral projections which engage the chip adjacent to the marginal portions of the shoe shank at the base of the heel, said remover being mounted for rock-

ing movement to equalize the bearing of said lateral portion upon the shank, means for holding the remover against the chip, and means for retracting the chip remover and 5 the knife together.

22. In a machine of the class described, the combination of a reciprocating knife, a stop arranged to engage the shank of the shoe, means operatively connected with the 10 stop to disconnect the knife from its operating mechanism to arrest movement of the knife when the shank is reached, and a foot on the stop having lateral extensions to bear only on the marginal portions of the shank.

23. In a machine of the class described, the combination of a reciprocating knife, a stop arranged to engage the shank of the shoe, means operatively connected with the stop to arrest movement of the knife when 15 the shank is reached, a foot on the stop having lateral extensions to bear on the marginal portions of the shank, and means for applying additional pressure to the foot to force the marginal portion of the shank 20 against the last before the knife is arrested.

24. In a machine of the class described, the combination of a reciprocating knife, a stop arranged to engage the shank of the shoe, means operatively connected with the 25 stop to arrest movement of the knife when the shank is reached, and a foot on the stop having lateral extensions to bear on the marginal portions of the shank, said foot being mounted upon the stop for rocking 30 movement to equalize the pressure on the marginal portions of the shank.

25. In a machine of the class described, the combination of a reciprocating knife, a stop arranged to engage the shank of the 40 shoe, means operatively connected with the stop to disconnect the knife from its operating mechanism when the shank is reached, said stop being mounted for movement out of operative position and out of 45 operative relation to said disconnecting means to permit access to the knife, and means for holding the stop in inoperative position.

26. In a machine of the class described, the combination of a reciprocating knife, a stop mounted for movement with the knife and for movement vertically relatively thereto, the stop having a normal position in 50 advance of the knife, means operatively connected with the stop for arresting the action of the knife, means for forcing the stop toward the knife to grip the chip, said stop being also mounted for movement out of operative relation to the knife arresting mechanism, and means for insuring restoration of 55 the stop in proper vertical relation to the knife arresting mechanism.

27. In a machine for breasting a heel after it is attached to a shoe, the combination of a reciprocating breasting knife, a shoe sup-

port movable with the shoe in the direction of the length of the shoe at substantially right angles to the plane of movement of the knife, and fingers having hooked ends arranged to extend from the rear of the shoe 70 forwardly to embrace the heel and determine by simultaneous contact of their hooked ends with the heel breast the longitudinal and angular position of the shoe relatively to the knife.

28. In a machine for breasting a heel after it is attached to a shoe, the combination of a breasting knife, a shoe support movable with the shoe in the direction of the length of the shoe and resiliently upheld for depression with and by the shoe, fingers having hooked ends arranged to extend from the rear of the shoe forwardly to embrace the heel and to determine the longitudinal and angular position of the shoe relatively to 80 the knife by simultaneous contact of the hooked ends with the heel breast when the shoe is allowed to be raised by the resiliently upheld support and the shoe is moved forward with its support to bring the breast in 85 contact with the hooked ends, and means for holding the support against depression during the operation of the knife.

29. In a machine of the class described, the combination of a breasting knife, means 95 for positioning the shoe relatively to the knife, comprising fingers having hooked ends arranged to embrace the heel and determine by contact of their hooked ends with the heel breast the longitudinal position 100 of the shoe, and means, operated by descent of the knife, first to separate the fingers and then to retract the fingers out of the path of the knife.

30. In a machine of the class described, the combination of a breasting knife, means for positioning a shoe relatively to the breasting knife, comprising normally separated fingers having hooked ends arranged to embrace the heel and determine by simultaneous contact with the opposite corners of the heel breast the longitudinal position of the shoe, means for separating the fingers to free the hooked ends from the heel and then moving the fingers rearwardly beyond 110 the plane of operation of the knife, and means for adjusting the fingers longitudinally of the shoe.

31. In a machine of the class described, the combination of a breasting knife, means 120 for positioning a shoe relatively to the breasting knife, comprising normally separated fingers having hooked ends arranged to embrace the heel and determine by contact with the corners of the heel breast the 125 longitudinal position of the shoe, means for adjusting the fingers longitudinally of the shoe, means for separating and withdrawing the fingers rearwardly of the shoe for the passage of the knife, and means for 130

- maintaining undisturbed the relation of the mechanism for separating and withdrawing the fingers as the fingers are adjusted longitudinally of the shoe.
5. 32. In a machine of the class described, the combination of a work support, a breasting knife, means for positioning the shoe, comprising fingers arranged to embrace the heel from the rear and to determine by contact with the breast face of the heel the longitudinal position of the heel, resilient means for holding the fingers in forward position, means for withdrawing the fingers rearwardly of the shoe prior to the breasting operation, and means for locking the fingers in withdrawn position. 70
10. 32. In a machine of the class described, the combination of a work support, a breasting knife, means for positioning the shoe, comprising fingers arranged to embrace the heel from the rear and to determine by contact with the breast face of the heel the longitudinal position of the heel, resilient means for holding the fingers in forward position, means for withdrawing the fingers rearwardly of the shoe prior to the breasting operation, and means for locking the fingers in withdrawn position. 75
15. 32. In a machine of the class described, the combination of a work support, a breasting knife, means for positioning the shoe, comprising fingers arranged to embrace the heel from the rear and to determine by contact with the breast face of the heel the longitudinal position of the heel, means for retracting the fingers prior to the breasting operation, and means for restoring the fingers to operative position becoming effective upon movement of the shoe support. 80
20. 32. In a machine of the class described, the combination of a breasting knife, means for positioning the shoe, comprising fingers arranged to embrace the heel from the rear and to determine by simultaneous contact with the breast face of the heel the longitudinal position of the heel, means for retracting the fingers prior to the breasting operation, and means for returning the fingers to operative position after the removal of the shoe out of range of the fingers. 85
25. 32. In a machine of the class described, the combination of a shoe support, a reciprocating breasting knife, means for positioning a shoe, comprising fingers arranged to embrace the heel and by contact with the edges of the heel breast to determine the longitudinal position of the shoe, said fingers being mounted for movement longitudinally of the shoe, resilient means for holding the fingers in their forward or operative position relatively to the shoe, means 90
30. 32. In a machine of the class described, the combination of a shoe support, a reciprocating breasting knife, means for positioning a shoe, comprising fingers arranged to embrace the heel and by contact with the edges of the heel breast to determine the longitudinal position of the shoe, said fingers being mounted for movement longitudinally of the shoe, resilient means for holding the fingers in their forward or operative position relatively to the shoe, means 95
35. 32. In a machine of the class described, the combination of a shoe support, a reciprocating breasting knife, means for positioning a shoe, comprising fingers arranged to embrace the heel and by contact with the edges of the heel breast to determine the longitudinal position of the shoe, said fingers being mounted for movement longitudinally of the shoe, resilient means for holding the fingers in their forward or operative position relatively to the shoe, means 100
40. 32. In a machine of the class described, the combination of a shoe support, a reciprocating breasting knife, means for positioning a shoe, comprising fingers arranged to embrace the heel and by contact with the edges of the heel breast to determine the longitudinal position of the shoe, said fingers being mounted for movement longitudinally of the shoe, resilient means for holding the fingers in their forward or operative position relatively to the shoe, means 105
45. 32. In a machine of the class described, the combination of a shoe support, a reciprocating breasting knife, means for positioning a shoe, comprising fingers arranged to embrace the heel and by contact with the edges of the heel breast to determine the longitudinal position of the shoe, said fingers being mounted for movement longitudinally of the shoe, resilient means for holding the fingers in their forward or operative position relatively to the shoe, means 110
50. 32. In a machine of the class described, the combination of a shoe support, a reciprocating breasting knife, means for positioning a shoe, comprising fingers arranged to embrace the heel and by contact with the edges of the heel breast to determine the longitudinal position of the shoe, said fingers being mounted for movement longitudinally of the shoe, resilient means for holding the fingers in their forward or operative position relatively to the shoe, means 115
55. 32. In a machine of the class described, the combination of a thin knife and a member engaging a substantial portion of a face of the knife and against which the knife is clamped to give it stiffness, and means 120
60. 32. In a machine of the class described, the combination of a thin knife and a member engaging a substantial portion of a face of the knife and against which the knife is clamped to give it stiffness, and means 125
65. 32. In a machine of the class described, the combination of a flexible knife, a forming member against which the knife is clamped to give it the shape of the forming member, and means for clamping together the side edges of the knife and forming member. 130
38. In a machine of the class described, the combination with a laterally curved knife, a laterally curved plate against which the knife is clamped, and relatively movable clamping members for clamping together the side edges only of the knife and plate. 70
39. A machine of the class described having, in combination, knife clamping mechanism comprising laterally movable grooved members, a knife sharpened at its end and adapted to be engaged at its side edges by the grooved members, and a member having approximately the shape of the knife and adapted to be clamped with the knife in the grooves in position to expose the edge of the knife. 80
40. In a machine of the class described the combination of longitudinally grooved clamping members mounted for rectilinear movement toward and from each other and means for effecting movement of the clamping members simultaneously to clamp a knife 90
41. A machine of the class described having, in combination, a laterally curved flexible knife, a plate having a different curvature from that of the knife against which the knife is clamped, and means for clamping together the side edges of the knife and plate to conform the curvature of the knife to the curvature of the plate and to hold the knife and plate rigidly. 95
42. In a machine of the class described, the combination of a knife, a knife holder having a groove to receive a side edge of the knife, and a stop in the groove of the holder 105
- to engage the knife and determine the position of its edge relatively to the holder.
43. A machine of the class described having, in combination, a knife, a knife holder having grooves to receive the side edges of the knife, and a shelf in one of the grooves to engage a corner of the cutting edge of the knife and determine its position relatively to the holder. 110
44. A machine of the class described having, in combination, a knife, a holder for the knife, a slotted forming plate against which the knife is clamped by the holder, and an abutment for the knife lying in the slot in the plate and engaging the end of the knife 115
- opposite its cutting edge to back up the knife for its cutting operation.
45. A machine of the class described having, in combination, a knife, a knife holder, a movable abutment for the knife, and means 120
- comprising a one-way clutch for preventing movement of the abutment by pressure against the knife edge.
46. A machine of the class described having, in combination, a knife, a knife holder, 125

an abutment for the knife, and a one-way clutch for the abutment which prevents movement of the abutment by pressure against the knife edge but permits the abut-

5 ment to be adjusted longitudinally against the back of the knife in the opposite direction.

47. A machine of the class described having, in combination, a knife, a knife holder 10 engaging the side edges of the knife, a plate against which the knife is clamped by the holder, and coöperating means on the plate and holder for insuring the positioning of the plate in the holder in a predetermined 15 position relatively to the holder.

48. In a machine of the class described, the combination of a knife comprising a cutting portion and a forming portion, the latter having a notch in its side edge, a 20 holder for the knife having grooves to engage the side edges of the knife, and a pin in one of the grooves to engage the notch in the forming portion to determine its position relatively to the holder.

49. A machine of the class described, having in combination, a knife comprising a thin cutting member and a thick stiffening and forming member having beveled side edges, clamping members having grooves 25 therein to receive the side edges of the knife and of the member, said grooves having the front wall inclined to receive the beveled edges of the forming member and having a bearing corner on the outer edge of the rear 30 wall to bear upon the cutting member and means for forcing the clamping members toward the side edges of the knife to clamp the cutting member and the forming member together.

50. In a machine of the class described, the combination of a knife, a knife carrier, a shoe support, a tread plate constructed and arranged to be operated to apply pressure to the heel of a shoe on the support, 45 and means constructed and arranged to store energy during the upward movement of the knife and to release that energy to operate the tread plate and hold the shoe clamped upon the support during the descent of the 50 knife.

51. In a machine of the class described, the combination of a reciprocating tool, means for operating the tool, a work support, means for clamping the work upon 55 the work support, and means constructed and arranged to store energy during one stroke of the tool and to release that energy to the work clamping means during the succeeding stroke of the tool.

52. In a machine of the class described, the combination of a reciprocating tool having an idle upward and an operating downward stroke, means for positively reciprocating the tool in both directions, means con- 60 structed and arranged to store energy due

to the momentum of the parts during the idle stroke and to release that energy to the tool during the operating stroke to accelerate the tool.

53. In a machine of the class described, 70 the combination of a work support, a breasting knife, a vertically reciprocating knife carrier, means for clamping the shoe upon the work support, means constructed and arranged to absorb the energy due to 75 the momentum of the knife carrier during its idle or upward stroke, said means being constructed and arranged to release that energy to the knife carrier and to the work clamping means during the downward 80 stroke of the knife.

54. In a machine of the class described, the combination of a work support, a breasting knife, a vertically reciprocating knife carrier, means for clamping the shoe 85 upon the work support, means constructed and arranged to absorb the energy due to the momentum of the knife carrier during its idle or upward stroke, said means being constructed and arranged to liberate the 90 stored energy to the knife carrier during the first part of the downward stroke and to the work holding means during the latter part of the downward stroke.

55. In a machine of the class described, a 95 reciprocating breasting knife carrier, a knife carried thereby, a tread plate to engage the tread face of the heel, a depressible work support movable into and out of position under the plate, means for applying 100 power pressure to the tread plate upon movement of the knife carrier, and means for locking the work support against depression which is rendered effective upon movement of the work support under the 105 tread plate.

56. In a machine of the class described, a reciprocating breasting knife, a tread plate, a work support movable into and out of position under the tread plate, said support being resiliently upheld to permit depression of the work and introduction of the work under the plate, means for preventing depression of the work and support after the work is positioned against the 115 tread plate, and means, becoming effective prior to the action of the knife upon the work, for applying pressure to the tread plate to hold the work.

57. In a machine of the class described, 120 the combination of breasting means, a tread plate, a work support normally depressible with and by the shoe, means for locking the work support against depression when the tread face of the heel is rested against said 125 plate, and means for exerting pressure upon the plate to prevent movement of the heel during the breasting operation.

58. In a machine of the class described, 130 the combination of breasting means, a tread

- plate, a depressible work support, means for locking the work support against depression when the tread face of the heel is rested against said plate, means for exerting pressure upon the plate to prevent movement of the heel during the breasting operation, and means for applying pressure to the lateral margins of the shank before the action of the breasting means is completed.
- 10 59. In a machine of the class described, the combination of breasting means, a tread plate, a depressible work support movable into and out of position beneath the plate having a surface to bear only upon the rear portion of the crown of the last, means insuring movement of the work support to its rearmost position beneath the last, means for locking the work support against depression when the tread face of the heel is rested against said plate, and means for exerting pressure upon the plate to prevent movement of the heel during the breasting operation.
- 15 60. In a machine of the class described, the combination of breasting means, a tread plate, a depressible work support having a surface to bear only upon the rear portion of the crown of the last, means for locking the work support against depression when the tread face of the heel is rested against said plate, and means for exerting pressure upon the plate to prevent movement of the heel during the breasting operation.
- 20 61. In a machine of the class described, the combination of breasting means, a tread plate having a roughened surface for engaging the tread face of the heel, a depressible work support having bearing only on the rear part of the crown of the last
- 25 and upon the forepart of the shoe, means for locking the work support against depression when the tread face of the heel is rested against said plate, and means for exerting pressure upon the plate to prevent movement of the heel during the breasting operation.
- 30 62. In a machine of the class described, the combination of a concave breasting knife, means for reciprocating the knife to breast a heel, a stop for the knife having a foot with lateral projections, and means for forcing the foot toward the knife to grip the side portions of the chip against the knife.
- 35 63. In a machine of the class described, the combination of a breasting knife, a stop arranged to engage a shoe shank to arrest the cutting action of the knife, means for forcing the stop against the heel breast prior to the completion of the cut of the knife, whereby as the cut is completed the knife will force the chip against the stop, and means for effecting the return of the stop in chip clamping relation to the knife.
- 40 64. In a machine of the class described, the combination of a reciprocating knife, a stop arranged to engage the shank of a shoe to determine the extent of the cutting action of the knife, and a foot on the stop having lateral extensions to bear on the marginal portions of the shank of the shoe, said foot being mounted on the stop for rocking movement to equalize the pressure on the marginal portions of the shank.
- 45 65. In testimony whereof I have signed my name to this specification.

LOUIS A. CASGRAIN.
